UNITED STATES PATENT OFFICE.

EMERY M. HAMILTON, OF NEW YORK, N. Y.

ELECTRIC TELEGRAPH TRANSMITTER.

SPECIFICATION forming part of Letters Patent No. 269,521, dated December 26, 1882.

Application filed March 23, 1882. (No model.)

To all whom it may concern:

Be it known that I, EMERY M. HAMILTON, of the city, county, and State of New York, have invented certain new and useful Improvements in Electric Telegraph Transmitters or other Analogous Electrical Instruments, of which the following is a specification, reference being had to the accompanying drawings, forming part of the same.

10 The invention relates to electric telegraph transmitters or other analogous electrical instruments, and particularly to the lever or bar therein that is intended to vibrate, in conjunction with the breaking and closing of the electric circuit, in the operation of telegraphing; and it consists in the peculiar construction and arrangement of said lever in its relation to the breaking and closing of the circuit, as herein-after described and claimed.

20 In the drawings I have shown my invention as applied to the common telegraph-key.

Figure 1 is a plan or top view of a key containing my invention. Fig. 2 is a side elevation. Fig. 3 is a central vertical section of 25 the same, and Fig. 4 shows a detached part of the side elevation.

A is the base plate or bar.

B B' are two screw posts or bolts, by which the instrument is secured to the table, and 30 with which the line-wires are connected. The post B' is insulated from the plate A by suitable insulating material, a, between the head b of said post and the sides of the opening in A through which B' passes, as shown plainly in 35 Fig. 3. c c' are the usual platinum contact-points.

C is the vibrating lever, by the movement of which the circuit is broken and closed in a transmitter. The hinge or joint upon which 40 the lever vibrates is formed of a projection or rib, e, extending across the upper face of the lever, which fits into a corresponding groove or channel, e', made in the under face of a fixed overhanging flange or bar, e², which may be 45 fixed and supported in its position by any suitable means. In the drawings it is represented as a flange projecting horizontally from the top of the abutment f, formed or secured on the base-plate A. The sides of the groove e' converge to form an angle at the bottom, and the rib e is formed to fit into and rock in the

groove as the lever is vibrated. This rib is preferably triangular in form, and is proportioned so that its upper edge or angle will fit into the groove so as to permit no lateral jar or movement, and whereby the lever will be caused to always vibrate in precisely the same plane. To this end the angle of the groove must be sufficiently small to prevent the said rib from sliding upward on the sides of the 60 groove by any side thrust or pressure on the opposite vibrating end of the lever under the hand of the operator, and the angle of the rib must of course be somewhat less than that of the groove to permit it to rock therein. The 65 rib e and groove e' may be reversed—that is to say, the groove may be made in the lever and the rib be formed on or secured to the flange e².

I have thus described what I regard as the 70 best form of a pivotal joint in the vibrating lever in the class of telegraphic instruments referred to; but it is obvious that the precise form described of the parts may be somewhat varied without departing from the spirit of my 75 invention. The apex of the rib and the bottom of the groove e' need not form sharp angles. They may be somewhat rounded, if preferred, the essential thing being that when the rib is pressed into the groove by a spring or its 80 equivalent, while the lever is free to rock or vibrate on its pivot, a tight joint shall be maintained and all rattling and shaking or trembling of the lever on its pivot shall be prevented. Lateral motion or shifting of the lever in its 85 seat may be prevented by a stud or pin projecting from the inner face of the ledge f, that enters a slot or notch in the end of the lever, as indicated by dotted lines at h in Figs. 1 and 2.

90 D is a set-screw that works in a threaded aperture through the lever C, near its pivotal end. This screw is hollow or recessed, as shown plainly in Fig. 3. k is a spiral spring placed in the said screw, its lower end resting on the 95 plate A. This spring acts to swing the lever upward, and at the same time to press the parts forming the pivotal hinge into firm and steady contact.

The tension of the spring may be varied and 100 adjusted by turning the screw D in or out. The long leverage thus secured permits the

use of a very stiff quick-acting spring, while it enables the lever to be vibrated with exceeding ease and precision.

I am aware that a similar spiral spring for a similar purpose in a transmitter has had the upper end of the wire of which the spring has been formed straightened and set in a small socket or hole in the end of a set-screw connected with the lever, as shown in the United States Patent No. 232,007, issued to Patrick B. Delany, September 7, 1880; but the placing of the end of the wire in such a hole or socket, as shown in said patent, is merely for the purpose of preventing the slipping of the upper end of the spring out of adjustment with the lever. I disclaim such device, and limit my claim to the combination of the set-screw D and the spring k, when the said set-screw is recessed, so as to receive the body of the spiral spring within the recess, thereby permitting the base A and the lever C to be placed near together, and yet a spring to be used of sufficient length to have the requisite resistance and resiliency.

E is a set-screw at the opposite or vibrating end of the lever. The head d of this screw constitutes the button or finger-piece of the lever. The lower end is provided with a small button or disk, d', which takes under a projection, d'', in the end of the plate A. This serves to limit the upward movement of the lever. By turning the screw down the movement is enlarged, and by turning it back it is decreased. This construction and arrangement of parts enables the operator to adjust the distance of vibration of the lever very conveniently and without removing his finger from the button.

F is the switch for closing the circuit when not operating. The head of the screw D, the button d, and the handle i of the switch are all made of or covered by rubber or equivalent non-conducting material, so that the operator will not in operating or adjusting the key have to touch any part that is a conductor of electricity. A short upwardly-projecting stud near the end of the base-plate A, provided with a projecting disk or flange on its upper end for engagement with the disk or flange d', would be the equivalent of the projection d.

The arrangement and relative position of the several parts I have described and shown are essential to the operation of the instrument as intended. The hinge on which the lever vibrates must be formed and arranged, as described, so that the parts are forced into contact by an upward pressure, or in the direction opposite to that of the hand or finger of the operator when pressing the lever to close the circuit. Then, as it is obvious, such pressure will co-operate with the spring that acts to force the parts into contact. This permits the break-circuit points to be placed intermediate the pivotal joint and the vibrating or button end of the lever, thus obviating by a slight yielding or spring-like action of the

lever the solid anvil-like resistance of the contact-points, so disagreeable to the operator when such points are immediately under his hand, and giving the advantage of leverage in pressing the points into contact. When the pivotal joint is placed underneath the lever, and the parts are forced into contact by the downward pressure of a spring, as in the English Letters Patent No. 2,525 of A. D. 1869, it is necessary to place the break-circuit points under the hand of the operator, or at the finger or button end of the lever, as, if placed intermediate the ends of the lever, such points acting as a fulcrum, the tendency of the hand of the operator at every downward movement must be to rock the lever on such fulcrum and throw the pivotal end upward and out of contact with the lower part of the joint. I disclaim all that is set forth in the English patent referred to.

It is also important, in order that there may be the least possible resistance to the vibration of the lever from its own inertia, that the pivotal joint should be as near as may be in the plane of the longitudinal axis of the lever, as it is shown in the drawings. If the pivotal line or point is above or below such plane, then, as is obvious, the entire lever will rock on the arc of a circle whose radius is equal to the distance from the pivotal line or point to the said plane of the lever. Under these circumstances the resistance to vibration resulting from the inertia of the lever would be considerable, and just to the extent that its inertia is encountered would the ease and delicacy of its movement be diminished. In the English Patent No. 2,525 of 1869, before referred to, the objectionable feature here pointed out appears, which, as I have indicated, is remedied by locating, as I do, the pivotal point or line in or very nearly in the plane of the longitudinal axis of the lever.

What I claim as my invention, and desire to secure by Letters Patent, is—

1. In a telegraph-transmitter, the lever C, the pivotal joint of which is composed of the upwardly-projecting rib e and the corresponding groove or channel, e', in the under side of the ledge or plate e'', together with the spring k, located underneath the said lever near its pivotal joint, and between the said joint and the break-circuit points c c', the said points being located between the said spring and the button or free end of the lever, all arranged and combined to operate as and for the purpose described.

2. In a telegraph-transmitter, the lever C, the pivotal joint of which is composed of the rib e and the corresponding groove, e', the pivotal line of the said joint being in or nearly in the plane of the longitudinal axis of said lever, together with the spring k and break-circuit points c c', all constructed, combined, arranged, and located relatively to one another as described.

3. In a telegraph-transmitter, the combination, with the vibrating lever C and base-plate A, of the recessed set-screw D and spring k,

the coiled body of which is located in said recess, all combined and arranged substantially as and for the purpose described.

4. The combination, with the lever C and base-plate A, of the adjustable set-screw E, provided at its lower end with a disk, d', constructed and arranged to engage with the under side of the projection d, as and for the purpose described.

10 5. The combination, with the lever C and

base-plate A, provided with the projection d², of the adjustable set-screw E, provided with the disk d' and the button d, as and for the purpose described.

Witness my hand this 17th day of March, 15
A. D. 1882.

EMERY M. HAMILTON.
